UNITED STATES PATENT OFFICE.

KARL MAUS, OF BERLIN-CHARLOTTENBURG, GERMANY.

DESICCATING AND COMPRESSING PULPY MATERIAL, PARTICULARLY PEAT.

Application filed April 27, 1921. Serial No. 465,033.

To all whom it may concern:

Be it known that I, KARL MAUS, of Knesebeckstrasse 6/7 Berlin-Charlottenburg, a citizen of the Republic of Germany, have invented new and useful Improvements in Desiccating and Compressing Pulpy Material, Particularly Peat (for which I have filed an application in Germany, May 31, 1919), of which the following is a specification.

The present invention refers to improvements in and relating to the drying and pressing into shape of material containing a large percentage of water, in particular peat, and it consists in a process and a new and improved press, which allow the highest possible extraction of the moisture without previous and subsequent drying of the peat or the like, and which result in the production of press-pieces, which are in suitable condition and form for immediate use as burning-material or for immediate transportation over great distances.

Whilst the ordinary wet peat contains from 85 to 90 per cent of water, according to the present invention approximately five sixths of the original moisture may be extracted therefrom; and further it is important, that by the present invention press-pieces or blocks may be produced which have scarcely one-third the original volume of the wet peat, and which blocks, owing to their particular shape, can be easily divided into small pieces, which, compared with other pieces of ordinary machine-peat of equal volume, are about double the weight of the latter, and which, compared with other pieces of spade-peat of equal volume, are about four times the weight of the latter, as has been proved by actual trials, when wet peat from the same source has been used for comparative trials of these three different methods.

According to the working-process and in the press of the present invention those advantages are obtained by subjecting the wet or pulpy material, within suitably formed press-chambers, to a prolonged and gradually applied pressure, for instance by pressing it for the time of 10 to 20 minutes by a pressure gradually rising up to 5 to 8 atmospheres. It is an important feature of my invention, that by a suitable construction of my press the water or other liquid is well drained out of the material to be dried, whilst even the finer particles of the ma-

terial itself are retained, and their capillarity is not destroyed, so as to facilitate a later perfect-air-drying of the drained and shaped press-pieces, if such additional air-drying should be deemed desirable. In order to obtain such results, according to my invention the draining and shaping process is carried through in a press or in a press-chamber having sieve-like acting walls, which sieve-like action is obtained by providing a permeable lining at all parts of the press-chamber, of the press-piston and of special partitions, arranged within the press-chamber, between which parts the material is pressed. In order to carry this principle into practice the permeable lining is formed by arranging upon each other several layers of wire-netting of different mesh and wire-thickness, the netting of finest mesh and wire-thickness being arranged nearest to the substance to be pressed, and the coarsest mesh and wire-thickness being arranged nearest to the walls of the press-chamber, the press-piston and the partitions. In certain cases however the permeable lining of the press-cylinder or the side walls of the press-chamber are not formed by a wire-netting but by a kind of grating arranged in the direction of the stroke of the press-piston, whereby the preferably metallic bars of the grating consist of smooth profile-wires or channelled rods with the spaces between the wires increasing gradually towards the outside.

Another important feature of my invention consists, in the case of press-chambers having considerable length or height, in the arrangement of movable partitions within the chamber, so as to divide the material to be pressed into a number of parallel layers perpendicular to the stroke of the press-piston, whereby those partitions are provided likewise with a permeable lining made of wire-netting or grating, so as to facilitate the draining-off of the water or other liquid. Furthermore, according to my invention the pressing walls of the piston, of the partitions, and of the bottom of the press-chamber are preferably so shaped, as to produce press-pieces, the middle part of which is thinner than the outer part of them, which form facilitates the draining-off of the water and the subsequent air-drying of the press-pieces, if such air-drying should be regarded as desirable. Besides that, in a further development of my process and my

press, projections are arranged on the pressure surfaces of the movable partitions, of the press-piston, and on the press-chamber which projections, by indenting the press-piece, promote the draining-out of the water and the subsequent air-drying of the press-cake; and which projections furthermore facilitate a later dividing of the large press-cakes into smaller pieces of practically equal size and weight, such as are most convenient for use as a fuel.

I shall now proceed to specifically describe the invention in detail with reference to the drawings of some preferred embodiments for executing my improved drying and shaping process, in which drawings—

Fig. 1 shows diagrammatically a vertical longitudinal section through a drying and shaping press-chamber or press;

Fig. 2 shows a cross-section and a plan-view of the movable partition walls, which may be inserted into the press-chamber or press;

Fig. 3 shows a somewhat more detailed longitudinal vertical section through an improved press-chamber or press, in which the press-piston and the movable partitions are provided with the above mentioned additional projections;

Fig. 4 shows in an enlarged scale a section through the permeable lining for the walls of the press-chamber or press, which lining is formed by several layers of wire-netting arranged upon each other;

Figs. 5 and 6 show likewise in an enlarged scale a vertical and a horizontal section through a part of a press-chamber or press, in which the permeable lining for the walls is made up by a vertical grating of profile-wires or channelled bars.

Now as to the details of the drawings in Figure 1 *a* is the wall and *d* the bottom of the press-chamber, into which the press-piston or plunger *f* may be depressed. The inside of the press-chamber *a* is provided with the permeable lining *c*, which according to Figure 1 is not made in one piece, but consists of a number of separate parts, or ring-sections in a cylindrical press-chamber, which ring-sections are of correspondingly small height and fit together, to form the press-mould proper or inner lining of the press-chamber. This considerably facilitates and simplifies the fitting and the removal of the sieve-lining; as well as the repair and the renewal of the individual parts.

The press-chamber having considerable length or height, it is further subdivided by a number of movable partitions *b*, which, according to the Figure 2 may be formed by a lens-shaped central core *b*₂, provided at both surfaces with a number of projecting ribs *b*₁, between which ribs are left flatter parts *b*₂. In consequence of the particular lens-shaped form of the partitions the peat or other

pulpy material *k* is pressed to the form of circular cakes the central part of which is thinner than the outer part of it, the advantages of which form are already explained above. In press-chambers having a smaller diameter the subdividing ribs on the partitions may be dispensed with, but in all cases I prefer to provide the movable partitions also with a permeable lining of wire-netting, as indicated in Fig. 1, and as it will be further detailed further down with reference to Figure 4.

In the more detailed drawings of Figures 3 and 4 again *a* is the outer wall of a cylindrical press-chamber, which wall is perforated by a greater number of slightly inclined bores *m*, for the immediate draining out from the press-chamber of the water or liquid, which is pressed out of the peat or other pulpy material *k*.

Inside of this cylindrical wall *a* is provided the permeable lining *h*, which, according to Figure 4, is formed by three layers *h*₁, *h*₂, *h*₃, of wire-netting, having different degrees of mesh-openings and wire-thickness, in such an arrangement, that the layer nearest to the press-pieces *k* is a fine, smooth net *h*₁ of about 1 millimeter mesh-opening and wire-thickness or less than that, whilst the following layers are of larger mesh and wire-thickness and the coarsest layer *h*₃ is placed on the side of the outer wall *a* of the press-chamber.

In consequence of this arrangement the very close-meshed first sieve-layer *h*₁ will retain even the very fine particles of the peat, so as to form, together with the latter, a sort of felt-filter, through which during the subsequent pressing-operations

the water can freely penetrate, whilst the peat-fibres are not allowed to escape. The coarser layers of netting on the outside of the lining allow the water to pass practically without hindrance, so that nowhere and at no moment will the flow of the drained-off water be choked up.

The peat or other material *k* to be pressed is, in the embodiment of the Figure 3 in the same way as in the previous example, subdivided by movable horizontal partitions, which are inserted into the press-chamber at equal intervals, in order to insure a more uniform and thorough extraction of the moisture from the press-cakes.

Again those partitions consist of a lens-shaped central core *n* of some firm material, which will stand the pressure, for instance wood, with an upper coat *q* and a lower coat *p* of wire-netting, or better still, the partitions may consist of baskets of firm hoop or channelled iron.

At the lower sides of the partitions and of the press-piston are provided projections *r*, which likewise are covered with a coat of wire-netting, as described above.

On the upper sides *q* of the partitions *n* are placed special perforated or openwork trays

g, into which the material to be pressed is filled, so that after pressing and shaping the material the trays *g* with the finished press-cakes may be lifted out of the press-

5 chamber and transported to the store-room, without difficulty and without fear of breakage.

In the construction of a press-chamber, which is shown in the Figures 5 and 6, the outer wall *s* of the chamber is formed by a perforated sheet-metal, and the inner permeable lining *t* consists of a vertical grating. The bars of the grating are profile-wires, which are arranged in such a way, 10 that their broader sides are directed towards the inside of the press-chamber and touch each other or leave only a very small fissure of about one millimeter between them, whilst the smaller sides of the grating-bars are 15 fastened to the hoops or rings *w*, made out of iron-rods, which rings *w* at the same time keep the bars of the grating at the right distance from the outer wall *s*.

The working-process and the construction 20 of the presses according to my invention is further improved by introducing a relative movement of the different parts of the press with regard to each other, for instance by imparting a slowly revolving movement to the bottom of the press-chamber or the inner wall of a ring-shaped series of a plurality of pressing-chambers adjoining each other. Such relative movement between some parts of the press or the press-chamber 25 will result in an opening of the capillaries of the peat, increasing thus the degree of the extraction of the water. Furthermore, another step in improving the working-process consists in heating the press or the press-chamber from without, as the heat causes a considerable swelling-up of the moisture-filled capillaries, in consequence of which the draining-off of the water is greatly increased.

45 It is understood, that the new and improved working-process of my invention may be carried through in presses of most various kinds and sizes; but special advantages will be obtained by using cylindrical presses with tilting-cylinders, out of which the finished press-cakes can be ejected by some suitable discharging-device. The presses may be actuated by hydraulic, electric or any other suitable drive. In the 50 case of submerged bog-peat, the peat-pressing-plant, suitably provided with several press-cylinders, which are alternatively charged, may be erected on a flat-bottomed boat or tug together with all the auxiliary 55 machines, such as charging apparatus for the cylinders, grab slewing crane for lifting the wet or pulpy peat out of the bog, reserve filling cylinders, storing bins for the raw peat, ejecting device for removing the 60 finished press cakes and so on. In the case 65

of field peat or surface-peat, a similar plant may be erected on a portable platform on wheels.

I claim:

1. In a device for compressing, desiccating and shaping peat and other pulpy material, means for compressing said material into cakes, and means for gradually increasing the compressing pressure towards the center portion of the material. 70

2. In a device for desiccating and shaping peat and other pulpy material, means for compressing said material into cakes, means for subdividing the material, and means for submitting the central portion of 80 the subdivided material to a relatively increased compressing pressure.

3. In a device for desiccating and shaping peat and other pulpy material, means for compressing said material into cakes, means for increasing the compressing pressure towards the inside of said material, and means for submitting the outer portions of 85 the material to capillary action.

4. In a device for desiccating and shaping peat and other pulpy material, means for superimposing separate layers of the material, means to submit the superimposed layers to compressing and capillary action, and means for increasing the compressing pressure on the inner portions of the superimposed material relatively to the pressure on the outer portions thereof. 95

5. In a device for desiccating and shaping peat and other pulpy materials, means for submitting the material to compressing and condensing pressure gradually increasing towards the center portion thereof, and means for submitting the less compressed and condensed portions to capillary action. 100

6. In a device for desiccating and shaping peat and other pulpy material, means for compressing the material into cakes, means for submitting the central inner portion of the material to a higher pressure than the outer portions thereof, and means for indenting and subdividing the press cake during compression. 110

7. In a device for desiccating and shaping peat and other pulpy material, means for submitting said material to compressing condensing and capillary action, means for increasing the compressing condensing pressure towards the central inner portion of the material, and means for indenting and subdividing the press cake during compression. 115

8. In a device for desiccating and shaping peat and other pulpy material, an enclosure comprising a plurality of closely superimposed outwardly progressively larger meshed sieve-like surfaces, and means for submitting the material to an inwardly progressing condensing and compressing action 125 within said enclosure. 130

9. In a device for desiccating and shaping peat and other pulpy material, an enclosure, comprising a plurality of closely superimposed outwardly progressively larger meshed sieve-like surfaces, a plurality of capillary, outwardly larger apertured, substantially parallelly spaced dividing means, transversely disposed in said enclosure, and means for submitting portions of the material to an inwardly progressing compressing and condensing action between said dividing means. 75
10. In a device for desiccating and shaping peat and other pulpy material, means for submitting said material to compressing condensing and capillary action, means for increasing the compressing condensing pressure towards the inside and central portion of the material, and means for subdividing the material during compression. 80
11. In a device for desiccating and shaping peat and other pulpy material, means for submitting separate, superimposed portions of the material to compressing and capillary action, means for moving said portions, and means for increasing the compressing pressure towards the inside and central portions of the material. 85
12. In a device for desiccating and shaping peat and other pulpy material, means for submitting separate, superimposed portions of the material to compressing and capillary action, separating means for said portions, a pervious enclosure around said material, means for moving the portions of material relatively to each other and relatively to said enclosure, and means for increasing the compressing pressure towards the inside and the central parts of the different portions of material. 90
13. In a device for desiccating and shaping peat and other pulpy material, moving means for said material, and means for submitting it while in movement to capillary compressing action, and means for increasing the compressing action towards the inner, central portions of the material. 95
14. In a device for desiccating and shaping peat and other pulpy material, an enclosure, inwardly widening capillary means on said enclosure, a plurality of movable, substantially parallelly spaced dividing means transversely disposed in said enclosure and comprising each a plurality of closely superimposed outwardly progressively widening capillary means, means for moving and compressing portions of the material between said dividing means, means for increasing the compressing pressure towards the inner central parts of each portion of material, and means on the dividing means for indenting and subdividing the material during compression. 105
15. In a device for desiccating and shaping peat and other pulpy material, a previous capillary enclosure, and a plurality of outwardly convex, substantially parallelly disposed compressing means within said enclosure. 110
16. In a device for desiccating and shaping peat and other pulpy material, a capillary enclosure, and a plurality of outwardly convex, substantially parallelly disposed compressing means in said enclosure, and projections on said compressing means. 115
17. Desiccating and compressing device for pulpy material, comprising the combination with an enclosure and feeding and educting means on said enclosure, of movable partitions in said enclosure, and compressing means operatively engageable with said movable partitions. 120
18. Desiccating and compressing device for pulpy material, peat and the like, comprising the combination with an enclosure, of partitions of partially increased height, axially movable in said enclosure, and porous lining on said partitions and on the inside of said enclosure, and compressing means, engageable with said partitions. 125
19. Desiccating and compressing device for pulpy material, comprising the combination with an enclosure and educting means on said enclosure, of a porous lining on the inside of said enclosure, loosely and substantially parallelly inserted substantially lenticular partitions axially movable in said enclosure, and compressing means engageable with said partitions. 130
20. Desiccating and compressing device for pulpy material, peat and the like, comprising the combination with an enclosure and educting means on said enclosure, of a plurality of substantially lenticular loosely and parallelly inserted partitions in said enclosure, an outwardly progressively larger apertured lining on said partitions, and an outwardly progressively larger apertured inside lining on said enclosure, and compressing means, engageable with said partitions. 135
21. Desiccating and compressing device for pulpy material, peat and the like, comprising the combination with an enclosure and educting means on said enclosure, of a plurality of outwardly bulged loosely and substantially parallelly inserted partitions on said enclosure, projections on one side of said partitions, an outwardly progressively larger apertured lining on said partitions, and an outwardly progressively larger apertured inside lining on said enclosure, and compressing means, engageable with said partitions. 140
22. Desiccating and compressing device for pulpy material, peat and the like, comprising the combination with an enclosure and educting means on said enclosure, of a plurality of inwardly convexly enlarged loosely and substantially parallelly inserted

partitions in said enclosure, rib shaped projections on one side of said partitions, and open trays on the other side of said partitions, an outwardly progressively larger 6 apertured lining on said partitions and an outwardly progressively larger apertured inside lining on said enclosure, and compressing means engageable with said partitions.

23. Desiccating and compressing device for pulpy material, peat and the like, comprising the combination with an enclosure and educting means on said enclosure, of a plurality of substantially lenticular, loosely 15 and substantially parallelly inserted partitions in said enclosure, a porous inside lining on said enclosure, comprising a plurality of closely superimposed outwardly progressively larger meshed layers of wire 20 gauze in contact with said partitions, open work portions on said partitions, and compressing means engageable with said partitions.

24. Desiccating and compressing device 25 for pulpy material, peat and the like, com-

prising the combination with an enclosure, of downwardly sloping educting ports in said enclosure, a porous inside lining on said enclosure, comprising a plurality of closely superimposed outwardly progressively larger 30 meshed layers of wire cloth, a plurality of substantially lenticular loosely inserted partitions in said enclosure in contact with said lining, open work portions on said partitions and compressing means engageable with said 35 partitions.

25. Desiccating and compressing device for pulpy material, peat and the like, comprising in combination, a receptacle, educting means in the walls of said receptacle, a 40 revolving bottom on said receptacle, a sieve like outwardly larger apertured inner lining on said receptacle, a plurality of partially outwardly bulged partitions, loosely inserted 45 in said receptacle, projections on said partitions and compressing means engageable with said partitions.

In testimony whereof I affix my signature.

KARL MAUS.
